UNITED STATES PATENT OFFICE

2,521,092

GAS RANGE STRUCTURE

Best Pratt, Chicago, Ill., assignor to Certified Gas Equipment Company, Chicago, Ill., a corporation of Illinois

Original application December 18, 1939, Serial No. 309,869. Divided and this application June 20, 1944; Serial No. 541,162.

3 Claims. (Cl. 277—59)

1

The present invention relates to gas range structures. This application is a division of my application for Gas Range Structure, Serial No. 309,869, filed December 18, 1939, now U. S. Patent 2,376,273, issued May 15, 1945.

The principal objects of the invention are to provide valve and burner devices for use with a gas range and which devices are economical in manufacture, capable of ready assembly, and provide a highly efficient flame with economical gas consumption. The invention includes valve structures, manifolds, mixing tubes and burners, as well as arrangements for supporting a pilot burner.

Other objects and advantages of the invention will be apparent from the following specification and attached drawings wherein:

Figure 1 is a plan view of the structure of the invention, with portions removed.

Figure 2 is a side elevation.

Figure 3 is a top plan view of a manifold.

Figure 4 is a front elevation of a manifold.

Figures 5 to 9 are vertical sectional views on the lines 5—5 to 9—9, respectively, of Figure 4.

Figure 10 is a front elevation of the manifold and valve structure.

Figure 11 is a top plan view of the valve structure with the front portion of the mixing tubes shown in horizontal section.

Figure 12 is a front view of a valve structure.

Figure 13 is a horizontal sectional view on the line 13—13 of Figure 12.

Figure 14 is a vertical section on the line 14—14 of Figure 13.

Figure 15 is a vertical section on the line 15—15 of Figure 13.

Figure 16 is a rear view of the body casting of the valve structure.

Figure 17 is a vertical sectional view on the line 17—17 of Figure 13.

Figure 18 is a vertical section of the lines 18—18 of Figures 13 and 16.

Figure 19 is a vertical section on the line 19—19 of Figure 13.

Figure 20 is a transverse vertical sectional view on the line 20—20 of Figure 17.

Figures 21 to 24 are front elevations of the valve and seat showing various positions of the valve.

Figure 25 is a rear view of a valve seat element.

Figure 26 is a view showing the closed position of a valve.

Figure 27 is a rear elevation of a valve disc.

As best shown in Figure 1, the burner and valve structure included in the present invention comprises equipment for use in the top

burner box of a range. This structure, when assembled, consists of a gas supply manifold or yoke 10 adapted to extend across the front of the burner box and connected at its central portion to a gas supply pipe 11 which extends from front to rear of the burner box. The manifold 10 may have an oven valve structure 12 connected and supported upon its central portion and, at each end, the manifold 10 supports a valve structure 13. Each valve structure 13 is provided with two burner controlling valves 14. On each valve structure 13, one valve 14 communicates with a gas and air mixing tube 15 which directs gas and air to a front burner of the burner box. In Figure 1, one mixing tube 15 is shown connected to a main burner 17 of large capacity and to a simmer burner 18. The other front mixing tube 15 directs gas and air to a main burner 19 of average capacity and also to a simmer burner 18. The other valve 14 of each valve structure 13 directs gas and air to a mixing tube 16 of sufficient length to extend to the rear burners of the burner box. In Figure 1, one of the mixing tubes 16 has a main burner 19 of average capacity connected thereto and also a simmer burner 18. The other rear burner mixing tube 16, for purposes of illustration, is simply shown provided with a simmer burner 18.

It will be understood that the arrangement of the burners of Figure 1 is merely for purposes of illustration. Also, in some instances, some of the burners might be of single type and would be connected to valves adapted to control such burners.

In order to provide for ignition of the various burners, a gas supply tube 20 extends from one of the valve structures 13 to a point centrally located with respect to the four burners, the pipe 20 being upturned at its free end as best illustrated in Figure 2 and provided with a suitable pilot jet 21. The pilot jet 21 is positioned within an annular fitting 22 provided with lateral apertures in which ignition tubes 25 are supported. One of the tubes 25 extends from the housing 22 to each burner so that the burners may be ignited from the pilot jet 21 as hereinafter described. The pilot housing 22 includes a downwardly extending threaded portion 26 (Figure 2) which is fitted in an aperture of a cross bar 27, a nut 28 being threaded upon the extension 26 beneath the cross bar to hold the housing connected to the latter. The cross bar 27 has apertures in its ends which are adapted to fit upon the pins or lugs formed in the rear burner mixing tubes 16.

By this arrangement, since the pilot burner tube 20 and its jet 21 are

not connected to the pilot burner housing 22, the housing, together with the tubes 25 and cross bar 27, may be readily removed from burner structure.

The manifold

The manifold or yoke 10 is best shown in detail in Figures 3 to 9 and consists of a hollow body portion 35 of tubular form, preferably rectangular in cross section as shown in Figure 9, and provided at its central portion with an enlarged rearwardly extending boss 36 which is threaded to receive the gas supply pipe 11. As appears in Figure 6, the upper portion of boss 36 is provided with a threaded aperture 37 adapted to receive a nipple such as 38 and on which an oven burner 12 (Figure 1) may be mounted so that the oven burner will receive gas substantially directly from the gas supply pipe 11. It will be noted that boss 36 is enlarged above the body portion of manifold 10, but does not project below the lower surface of the manifold. This complies with usual working restrictions.

The interior passage 39 of the body portion of manifold 10 communicates with the boss 36 so that gas will flow from the boss and through the passage to right angled hollow upward extensions 40, one at each end of the body portion 10. As best shown in Figure 5, each extension 40 is open at its rear and upper face so that gas may flow from the extension to a valve or valve structure supported upon the latter. In order that a valve structure 13 may be secured to the manifold 10, each upward extension 40 is provided with a flange or ear flush with its rear face and having bolt receiving apertures 42 suitably spaced about the same. The flange 41 is preferably of substantially triangular form as illustrated in Figure 4. Beyond each upward extension 40 the main passageway 39 of the manifold 10 is threaded to receive a plug 43. As shown in Figure 1, one of these plugs may be replaced by a tube leading to a pilot burner.

It will be noted from Figures 3 to 9 that the manifold 10 is of minimum cross section and that the rear faces of the flanges 41 lie in the same plane as the rear wall of the manifold. By this arrangement, the manifold, as well as such valve structures as are connected thereto, will occupy a minimum space from front to rear of the range. Also, the fact that the rear surfaces of the flanges 41 are planar enables these surfaces to be readily and cheaply machined so that they may form an efficient seal with a burner structure connected thereto.

The valve structures

A valve structure 13 constructed in accordance with the present invention is best illustrated in Figures 10 to 27. Referring to Figures 13 to 15, it will be observed that each valve structure comprises a body casting 50 of substantially plate-like form and provided with a slightly forwardly projecting front central portion 51 having apertures 52 spaced therein in such arrangement that they will coincide with the apertures 42 of the flange 41 on a manifold 10. The body casting 50 also has apertured ears 53 formed upon its ends by means of which the valve structures, and thereby the manifold 10, can be connected to and supported upon the front portion of the burner box of a range. Such support is, of course, in addition to that provided by the main gas supply pipe 11. The front projecting portion 51 also includes the mouth of an aperture 54 adapted to be aligned with the outlet of the upper

extension 40 of the manifold 10. Aperture 54 extends entirely through the member 59 and its rear end is closed by a plug 54a.

Gas entering passage 54 will flow into a passage 55 which extends longitudinally of the body casting 50. As best shown in Figure 16, the passage 55 is formed in the lower portion of a rearward substantially U-shaped extension 56 of the body casting 50, which extension includes vertical legs 58. The passage 55 has vertical portions 57 within the extension legs 58. As best indicated in Figures 14, 15 and 18, the left hand vertically extended passage 57 has a further extension 59 leading upwardly therefrom. The ends of the horizontal passage 55 are adapted to be closed by threaded plugs 60, although as has been previously stated, one of these plugs may be replaced by a tube 20 leading to the pilot burner. In this way the pilot burner will receive gas entirely independently of the valves supported on the valve structures 13.

As illustrated by Figure 15, the right hand vertically extended passage 57 has a port 62 extending forwardly therefrom and opening to the front face 50a of the body casting 50. It will be noted that the port 62, serving as a gas supply port, opens to the front face 50a within a seat portion 63 bounded by a slightly forwardly projecting and rectangular shoulder 64. The area defined within the shoulder 64 is divided by a substantially diagonally extending shoulder 65 and a second diagonally extending shoulder which extends between the rectangular shoulder 64 and the first diagonal shoulder 65. By this arrangement, the area within the bounding shoulder 64 is divided into an enclosure 68 to which the supply port 62 opens, and a relatively large triangular enclosure 69, as well as a smaller enclosure 70. A port 71 extends from the enclosure 69 and through the solid extension 58 of the body casting 50 and, as best indicated in Figure 13, port 71 opens to a threaded bore 72 opening to the rear face of the extension 58. The bore 72 is adapted to receive a nipple 73 which, as subsequently described, is adapted to supply gas to the main burner of a burner device. A port 75 opens from the smaller enclosure 70 to a socket 76 (Figure 13) which carries a nipple 73. Nipple 73 is intended to be connected to the simmer burner of a burner device.

The vertically extended passage 59 of the left hand upward extension 57 of gas supply passage 55 opens through a port 80 to an enclosure or seat portion 81 included in a rectangular enclosure 63a bounded by a substantially rectangular shoulder 64a. The enclosure 63a is divided by diagonal shoulders 65a and 66a. The gas supply port 80 opens to the uppermost enclosure 81 of the three enclosures thus defined. From the smaller enclosure 82 there extends a delivery port 83 which opens to the rear of the corresponding solid extension 58 and is adapted to receive a nipple 73. As will be subsequently described, nipple 73 is intended to be connected to the simmer burner of a burner device. The larger enclosure 84 has a port 85 extending rearwardly therefrom to communicate with a nipple 73 arranged to supply gas to the main burner of a burner device.

It will be noted that the three enclosures 81, 82 and 84 of the left hand seat portion 63a, as well as the ports opening to the same are turned 180° with respect to the corresponding enclosures and ports of the right hand seat portion 63. The purpose of this will be subsequently apparent.

As best shown in Figure 13 and at the right hand portion of Figure 14, a valve body member 90 of rectangular outline and of the form best shown (in rear elevation) in Figure 25 is seated and secured to the right hand seat portion 63 of the body casting 50. The valve body element 90 comprises a flat front wall 91 (see also Fig. 13) and has a rectangularly extending shoulder 92 projecting from its rear face. The space defined within the shoulder 92 is divided by diagonal walls or shoulders 93 and 94 into a small enclosure 95, a somewhat larger enclosure 96 and a large enclosure 97.

Three ports are provided through the forward wall 91 of the element 90 as best shown in Figure 25 and at the right hand portion of Figure 14. The three ports are arranged along an arcuate line drawn from the center of the element 90, the lowermost port 100 opening from the chamber 96, the next port 101 opening from the small chamber 95 and the third port 102 opening from the chamber 97. When element 90 is applied to the right-hand portion 63 of the body casting 50 the diagonal shoulders 93 and 94 will be aligned with the diagonal shoulders 65 and 66 of the right-hand enclosure 63 (Figure 15) and, when thus applied, port 100 of element 90 will be a supply port, port 101 will be a simmer port and port 102 will be a main burner port.

The valve body element 90 has four screw receiving apertures therein, one at each corner and extending through the bounding shoulder 92. One of these apertures, designated by the numeral 104, is relatively large, while the three remaining apertures 105 are somewhat smaller than aperture 104. As shown in Figure 15, the right hand enclosure 63 of body casting 50 has four apertures about its edges and in the shoulder 64, the aperture 104a in the upper right hand corner being somewhat larger than the other three apertures 105a. These apertures are threaded to receive bolts. When the valve body member 90 is applied to the right hand enclosure 63 with the large bolt aperture 104 thereof aligned with the large threaded aperture 104a, the diagonal walls 93 and 94 will thus be exactly aligned with the diagonal walls 65 and 66 of the enclosure 63 as described above. Thus, as shown at the right hand portion of Figure 14, the body member aperture 100 will receive gas from the gas supply aperture 62 of the casting 50, valve body port 101 will be in position to supply gas to the simmer supply port 75 of the body casting 50 and the third valve body port 102 will supply gas to body casting port 71. While none of these sets of ports are in direct alignment, as indicated in Figure 14, nevertheless the chambers to which they respectively open, are in exact alignment.

The left hand enclosure 63a of casting 50 is also provided with four threaded apertures at its corner portions, but the largest of these apertures, designated by the numeral 104a, is at the lower left hand corner. Thus, in order to secure a body member 90 to the left hand enclosure 63a, it is necessary to turn the body member 180° from the position of the body member 90 on the right hand enclosure 63. As a result, as illustrated in Figure 14, the three ports 100, 101, and 102 of the body member will be respectively aligned with the gas supply chamber 81, simmer chamber 82 and main burner chamber 84.

The turning of the body member on the left hand enclosure 63a 180° with respect to that on the left hand enclosure 63 is due to the fact

that the simmer burner mixing passages, hereinafter described, communicate with the two innermost passages 75 and 93 of the four outlet passages, but, regardless of this, as hereinafter stated, each simmer burner must receive initial flow of gas and by valves rotating in the same direction. The use of separable body members 90 renders this possible.

Gaskets of suitable outline to form seals upon the shoulders of the opposed faces of the body casting 50 and the body members 90 may be provided as indicated in Figure 13 so that the two members will be in sealed relation, and the respective chambers on their opposed faces will also be sealed from each other.

The flow of gas from a supply port 100 to the simmer port 101 and main burner port 102 is controlled by a disc valve 108 shown in diametric section in Figure 13 and in rear plan in Figure 27. Referring to the latter figure, it will be observed that on its rear surface, the disc valve 108 is provided with an arcuate groove or passage 109 of sufficient length to completely bridge the three ports 100, 101 and 102, with a tail port 110 extending from its rear end, tail port being of reduced size, both as to width and depth. Figure 21 shows the normal position of the disc valve 108 upon the valve body 90 when the latter is applied to the right hand seat or enclosure 63 of the casting 50 and Figure 26 shows the normal closed position of the valve disc 108 on a body member 90 when the latter is applied to the left hand seal or enclosure 63a of the body casting 50. It will be noted that in Figure 26, the parts are turned 180° with respect to the showing of Figure 21.

The valve disc 108 is adapted to be rotated by a handle, not shown, applied to a shaft 112, the arrangement of the shaft with respect to the structure being best shown in Figures 13 and 17. The inner end of shaft 112 is fitted in a socket 113 on the forward face of the body member 90. As best shown in Figure 17, the entire inner portion of shaft 112 is flattened along one side to extend through a keyed aperture 114 in the valve disc 108 so that the latter will turn with the shaft. An inner housing 116 encloses the valve disc 108, housing 116 being of substantially cup-shaped form and having a bowed cruciform spring 117 positioned between its inner face and the outer face of the disc valve 108. The space within the inner housing 116 may be filled with grease to augment the seal between the body casting and the disc valve. Inner housing 116 is, in turn, enclosed by an outer housing 118 through which the outer end of shaft 112 projects. It will be noted that the extreme outer portion of shaft 112 is enlarged to provide a shoulder 119 at approximately the point at which it passes through the outer housing 118. However, the central aperture in outer housing 118 is of sufficient diameter that the enlarged portion of shaft 112 may freely move through the same.

A radially extending plate 120 is secured to the shaft 112 just inwardly of its shoulder 119, this plate being provided at its side edges with in-turned flanges 121 which extend along and enclose an arm 122 having a keyed connection with the inner and flattened portion of shaft 112. Arm 122 is held in embraced relation against the plate 120 by a coil spring 123 positioned between the outer surface of inner housing 116 and the arm 122. Thus the action of the spring 123 will

also be to force the plate 120 against the inner surface of the outer housing 118.

The arm 122 is provided at its outer end with an outwardly facing lug 124 with a tip 125 of reduced size. When the shaft 112 is in such position that the valve disc 108 carried thereby is in the closed position illustrated in Figures 21 and 26, the lug 124 on arm 120 will extend through a relatively large aperture 126 in the forward or plate-like surface of outer housing 118 and best shown in Figure 12. The shaft 112 will thereby be positively locked against accidental turning movement. When the shaft 112 is pressed inwardly against the action of spring 123 and turned to the position shown in Figure 22, so as to place the passage or groove 109 of valve disc 108 in bridging relation to the supply port 100 and the simmer burner port 101, the arm 122 will be opposite a smaller aperture 127 in the wall of outer housing 118. Aperture 127 is merely of such size as to receive the reduced and rounded tip 125 on the arm lug 124 with the result that the arm 122 and hence the valve disc 108 will not be locked in the Figure 22 position. However, since the arm 122 is being urged toward the outer housing front plate by the spring 123, the person operating the valves will be given an indication, by a clicking sound, of the fact that the valve disc 108 is at that moment in such position as to deliver gas to the simmer burner.

Further rotation of valve shaft 112 from the position of Figure 22 to that of Figure 23 will bring the tip 125 on the arm 122 into engagement with a second small aperture 128 in the outer housing 118. At this time, the groove 109 of valve disc 108 will entirely bridge the three valve body ports 100, 101 and 102 so that gas will be supplied from the supply port 100 to the simmer burner and main burner of a range. In order to reduce the flow to the main burners, that is, reduce the flow through the main burner supply port 102, the shaft 112 may be stopped just in advance of the position indicated in Figure 23 so that the arcuate leading end of the valve disc groove 109 will not entirely be in alignment with the main burner supply port 102. Obviously, if desired, the valve may first be turned to the Figure 23 position, which will be indicated by the engagement of stop tip 125 with aperture 128, and then may be turned backwardly to give the desired reduced flow to the main burner.

If a reduced flow to both the simmer burner and the main burner is required, the valve disc 108 may be turned forwardly from the position shown in Figure 23 to that illustrated in Figure 24 wherein the tail groove 110 of the valve disc 108 is opposite the supply port 100. At this position, an extremely reduced flow of gas will be supplied to both burners, but the flame will nevertheless be sustained. Such a point will, of course, vary with different burners and in order to make this position of the valve adjustable, a limit plate 130 including a rearwardly extending flange 131 (Fig. 20) is secured to the inner face of the plate-like portion of outer housing 118. By this arrangement, when the edge of arm 122 contacts with the inturned shoulder 131, the valve disc 108 will be in the position illustrated in Figure 24. The desired limit position of the valve can be adjusted by reason of the fact that limit plate 130 is provided with a small screw 132 which extends through an arcuate slot 133 in the outer housing 118. Obviously, the position of the limit plate 130 can be adjusted during assembly of the range and when the point at which a reduced

flow of gas to both burners has been ascertained.

It will be noted that all meeting or seating faces throughout the valve structure are planar, making it economical to machine and grind these faces to finished form.

It will be understood that all of the devices described herein may be used in a single assembly or may be used separately with other devices.

The terminology employed in the specification 10 is for the purpose of description and not of limitation, the scope of the invention being defined in the following claims.

I claim:

1. The combination in a gas range valve structure, of a body casting having two seat faces spaced thereon, each seat face including a supply port and a burner flow port, the arrangement of one of the ports of one seat face being oppositely arranged with respect to the ports of the other

20 face, ported seat members including front and rear faces of similar form on each of said seat faces, one of said seat members being oppositely arranged with respect to the other and each seat member including chambers in its rear face respectively opening to the supply and burner flow ports of the corresponding seat face and the chambers having ports opening to the front face of each seat member, and disc valves rotatable on said seat members.

30 2. A seat member for a rotatable valve and adapted to be mounted upon a manifold having a plurality of ports therein, said seat member having chambers in one face of sufficient size to accommodate various arrangements of manifold 35 ports and so that flow from one such port will be excluded from another such port, the other face of said seat member having ports therein each opening to one of the chambers, the seat member ports being arranged in a circular series so 40 that flow through the same may be controlled by a rotatable valve element.

3. In combination, a gas range manifold casting including a hollow portion to form a gas supply chamber, said hollow portion having a port 45 extending through one wall thereof, said casting including a solid, non-chambered portion having a bore extending therethrough, a planar valve body element having chambers in its rear surface positioned opposite said port and said bore, said chambers having ports extending 50 therefrom to the front face of said element and arranged on an arcuate line, and a disc-like valve having an arcuate passage therein adapted to bridge the ports of said valve body element.

BEST PRATT.
